ADJUSTABLE FASTENER

Alfred E. Carlile, Meadville, Pa., assignor to Talon,
Inc., a corporation of Pennsylvania

Application December 26, 1952, Serial No. 22,886

Term of patent 14 years

(Cl. D17—8)

To all whom it may concern:

Be it known that I, Alfred E. Carlile, a citizen of the United States, residing at Meadville, in the county of Crawford and State of Pennsylvania, have invented a new, original, and ornamental Design for an Adjustable Fastener, of which the following is a specification, reference being had to the accompanying drawing, forming a part thereof.

In the drawing:

Fig. 1 is a plan view of an adjustable fastener, showing my new design;

Fig. 2 is a side elevational view of the right side of the fastener shown in Fig. 1;

Fig. 3 is a side elevational view of the left side of the fastener shown in Fig. 1;

Fig. 4 is a bottom end view of the fastener; and

Fig. 5 is a top end view thereof.

I claim:

The ornamental design for an adjustable fastener, substantially as shown.

ALFRED E. CARLILE.
